COLOR CORRECTION

Alexander Murray, Rochester, N. Y., assignor to
Eastman Kodak Company, Rochester, N. Y., a
corporation of New Jersey

Application April 23, 1937, Serial No. 138,616

6 Claims.

This invention relates to photo-mechanical processes for the reproduction of a multi-colored original. It relates to the making of a color printer for use in such a process and more particularly to a color printer which is corrected for the limitations of the best contemporarily available inks.

It is an object of the invention to provide a method of making a color-corrected color printer.

Various methods of color correction generally called "masking methods" are well known. It is an object of the present invention to provide a method of color correction which might be termed "autographic" and which does not require the use of special masks but employs the original itself, or more exactly a color separation image of the original, to act as a mask.

The method provided by my invention is one in which neither the negative nor the color printer made therefrom is masked in the usual sense, but a corrected printer is made by direct exposure through an ordinary color separation negative.

It is a special object of my invention to provide a photo-mechanical process in which the density of the blacks and dark grays, i. e. areas where all three color printers have a relatively high printing density, are reduced (more or less proportionally).

It is a further object of my invention to provide a novel picture of a multi-colored original in which all the neutral density tones are reduced to a constant value and which comprises only color variations.

It is also an object of the invention to provide a method of making such a novel picture.

Although my invention may be practiced with various types of equipment, one form of apparatus which is particularly suitable for practicing one embodiment of my invention is described by F. Hahn in U. S. Patent 1,576,118.

Other objects and advantages of my invention will be apparent from the following description when read in connection with the accompanying drawing in which:

Fig. 1a shows a well-known manner of making a halftone color separation negative from a multi-colored original. This constitutes the first step of my process, one embodiment of which is shown in the form of a flow chart: Figs. 1a, 1b, 1c and 1d.

Fig. 1b shows one step, according to my invention, in making a color printer from the color separation negative shown in Fig. 1a.

Fig. 1c illustrates another step, also according

(CL 95-2) to my invention, in making a color printer from this negative.

Fig. 1d illustrates a corrected color separation positive or printer resulting from my process.

Fig. 2 illustrates a novel picture which can be made according to one embodiment of my invention.

My invention is primarily concerned with the making of a corrected color printer from a primary color separation negative which has been made in any of the usual ways. A positive made from a color separation negative may comprise the printer itself or the printer may be made therefrom by any suitable duplicating process. One well-known method of introducing color correction in the making of a color printer comprises masking certain of the color separation negatives with low-contrast positives made from other color separation negatives. Another method—namely that for which the above-mentioned Hahn apparatus was intended—introduces the color correction during the making of the negative, by exposing the sensitive negative material to a color separation image from the original, first through a negative mask corresponding to a correcting color (e. g. a red filter negative may be used to correct a green filter negative) and second, directly.

According to my invention, a method of introducing color correction is provided which does not employ either a negative mask (in making the negative) or a positive mask (in making the printer) in the usual sense of the word mask. Instead, I employ the original itself as the mask in the following manner. A color separation negative is made from the original and a positive is made from this negative by exposing a photographic layer twice through the negative, first to uniform illumination (preferably white light) and second, to a color separation image of the original. This last color is a correcting color, e. g. in making a magenta printer through a green separation negative, the second exposure may be made by a red separation image, that is by illuminating the negative with a red separation image of the original. This image may be a projected image of the original or it may be provided by placing the original in contact with the negative and illuminating it with colored light. The two exposures may be made simultaneously or successively in either order.

Throughout this specification and the accompanying claims I use the terms red, green, and blue to refer to the primary colors, i. e. the colors of the filters through which the separation nega-

tives are made. The complementary colors, i. e., the colors of the printers are called blue-green, magenta, and yellow respectively. In certain branches of press-printing work these complementary colors are called blue, red and yellow, but this latter convention and its accompanying confusion will be avoided in this specification. The term "photographic" is used in a broad sense so that "photographic layer" includes those used as photo-sensitive resists as well as the usual silver-halide emulsions.

I will now describe the particular embodiment of my invention which is illustrated in the accompanying drawing.

16 As shown in Fig. 1a, a multi-colored original 11, which may be either a transparency or an opaque painting or color photograph, is photographed by a process camera represented by a lens 13, in the image plane of which is placed a 20 film or plate 15. In this particular embodiment of the invention a halftone negative is produced by positioning a halftone screen 14 at a suitable distance in front of the sensitive layer of the film or plate 15. A primary color filter 12 (red, 25 green, or blue) is mounted in front of the lens 13 in any well-known manner. Any other suitable method of making a color separation negative may be employed.

30 After development, this film or plate 15 comprises a color separation negative 15'. As shown in Figs. 1b and 1c, a positive 17 is made from this color separation negative 15' by contact printing. In Fig. 1b, the negative 15' is illuminated by a color separation image of the original, by 35 means of a set-up similar to that shown in Fig. 1a, but employing a color filter 16 which transmits a color which is suitable for correcting the color printer corresponding to the color separation negative 15'. For example, it has been 40 found desirable to correct a magenta printer in proportion to the amount of red present in the original. In making a magenta printer, a green filter is used at 12 to make a green separation negative 15'. The exposure of the positive 17 illustrated in Fig. 1b is then made through a red filter 16.

45 In addition to this correcting color exposure, the positive 17 receives a direct exposure modulated by the negative 15' only. This may be accomplished in a simple manner as shown in Fig. 1c by placing a sheet of white material 18 in front of the original 11 and giving a white "flash" exposure.

50 After receiving the two exposures as shown in Figs. 1b and 1c, the photographic layer 17 is developed in any suitable and well-known manner to form a corrected color separation positive or printer 17' as shown in Fig. 1d.

55 As pointed out above, the steps shown as Figs. 1b and 1c may be performed in either order or simultaneously. One simple method of making these two exposures simultaneously is to use a color filter at 16 which is diffusing (i. e. translucent rather than transparent) over a predetermined portion of its area. This portion may be adjustable, for example, an adjustable sector of ground glass may partially replace or be superimposed on the color filter.

60 The step shown in Fig. 1c may be made in any 70 well-known manner, by contact printing, as shown, or by projection printing. In making this exposure, the illumination on the negative is uniform, preferably white. Since the sensitive layer 17 and the negative 15' are arranged in printing relation it is desirable to perform both exposures

without disturbing this relation. However, various arrangements may be used. For example, in making the steps shown in Fig. 1b, the negative 15' is illuminated by a color separation image of the original, which image may be a projected one 5 as shown or it may be the original itself. The negative 15' may be placed in contact and register with the original 11, which is then illuminated from in front or behind. If illuminated from in front (i. e. so that the light is reflected 10 to the lens 13) the density and contrast of the negative 15' is effectively doubled since the light must transverse it twice. A transparency is the more suitable form of original to be illuminated from behind. In fact, if the original is a transparency, all three elements—the original, the negative and the sensitive layer 17 may be superimposed in relative contact and illuminated by colored light.

15 As shown in Fig. 1a, I prefer to expose the negative 15' through the base. By doing this, the negative image 15' can be simultaneously placed in contact with the sensitive photographic layer 17 and in register with a color separation image of the original as shown in Fig. 1b. If the original 25 is a transparency, the negative 15' may be exposed directly and then both the original and the negative turned over in making the step shown as Fig. 1b. On the other hand, if the original is not a transparency and it is not desirable 30 to make the exposure of the negative 15' through the base as shown in Fig. 1a, a reflector such as a prism may be placed in front of the lens in performing the step shown as Fig. 1b. This reflector introduces the lateral inversion 35 necessary to permit the negative image 15' to be simultaneously in contact with the sensitive surface of 17 and in register with a color separation image of the original.

40 My invention is applicable to either continuous tone or halftone processes. In a halftone process, I prefer to introduce the halftone pattern by making each color separation negative through a halftone screen, as shown, but the halftone pattern may be introduced at a later stage such 45 as when the positive 17 is being exposed. If the original is a transparency and no enlargement or reduction is required, it is possible to perform my invention without the use of any camera, by using contact halftone screens and making all 50 exposures by contact as discussed above. That is, the color separation negative is made by contact printing and the positive is made therefrom also by contact printing.

55 Since according to the arrangement shown in the drawing, the image on 17 is laterally inverted with respect to the original, this positive may comprise the printer itself and a correctly oriented print will result therefrom. In photogravure work, the corrected positive 17 can, of 60 course, be used directly. However, if desired a negative may be made directly from the corrected positive 17 and any suitable type of printer made therefrom in a well-known manner.

65 Furthermore, according to my invention, I am able to provide a novel picture of a multi-colored original, in which all visual density gradations (i. e. all blacks, grays, and whites) are reduced to the same average gray tone, but in which the color variations are reproduced substantially correctly. Since all three color photography is based 70 on the sensitivity characteristics of the human eye, this novel picture is perhaps more accurately defined as one having only color variations and substantially uniform visual density. This is 75

shown in Fig. 2. In the more general case, the relative visual densities may be controlled within limits to any desired value. In a special case, the neutral densities—i. e. whites, grays and blacks are reduced to an average gray, but the density variations of certain colors are not so reduced.

One useful application of a novel picture having only color variations is as a test chart for the investigation of color blindness. As is known, color blindness test charts comprises areas which have practically identical visual densities but which differ slightly in hue. Indeed, it may be desirable in some cases to introduce a slight known difference in visual density as well as the difference in hue.

According to a special embodiment of my invention, a novel color picture of the above type having uniform visual density, is made up from three color printers each of which is made in the following manner. A color separation negative is made by any suitable system such as that shown in Fig. 1a. A printer or positive is made therefrom by any suitable system equivalent to that shown in Fig. 1b, wherein the color of the filter 16 is practically complementary to that of the primary color filter 12. No "flash" or exposure corresponding to that shown in Fig. 1c is given in this case. I have found that useful results are obtained when the color of the filter 16 is any spectral range not transmitted by the primary color filter 12.

By choosing certain color filters and/or giving a small flash exposure such as indicated in Fig. 1c a certain predetermined amount of density variation of the colors and/or the neutral tones, may be included as well as the color variation. Obviously, this permits many various types of color blindness test charts to be made.

Furthermore, this effect—namely the reduction of blacks to a gray—provides another important advantage to the first described embodiment of my invention. Those skilled in this art are aware that a reduction of the density of blacks and dark grays is desirable in many cases, and this reduction is inherently provided by a process which employs my invention to obtain color correction. At the same time, by choosing a suitable total exposure the highlights or white areas of the original are made to appear as zero printing density on each of the printers, in the usual way.

Having thus described one embodiment of my invention in detail and several ways in which it may be employed, I wish to point out that it is not limited to the specific arrangements shown but is of the scope of the appended claims.

What I claim and wish to protect by Letters Patent of the United States is:

1. In a photo-mechanical process for the reproduction of a multi-colored original, the method of making a corrected color printer which comprises making a color separation negative and making a positive therefrom by exposing a sensitive photographic layer to two separate exposures, one in printing relation to the negative uniformly illuminated and the other in printing relation to the negative illuminated by a color

separation positive image of the original, said last mentioned color being a correcting color and different from that corresponding to the negative.

2. In a photo-mechanical process for the reproduction of a multi-colored original, the method of making a corrected color printer which comprises making a color separation negative and making a positive therefrom by exposing a sensitive photographic layer in printing relation to the negative illuminated by uniform illumination and by a color separation positive image of the original, said last mentioned color being a correcting color and different from that corresponding to the negative.

3. In a photo-mechanical process for the reproduction of a multi-colored original, the method of making a corrected color printer which comprises making a color separation negative and making a positive therefrom by positioning a sensitive photographic layer in printing relation with the negative, illuminating the negative with uniformly distributed illumination and with illumination comprising a color separation positive image of the original, the amounts of said illuminations being in predetermined relation and said last mentioned color being a correcting color and different from that corresponding to the negative, and developing the layer.

4. In a photo-mechanical process for the reproduction of a multi-colored original, the method of making a corrected color printer which comprises making a color separation negative of the original and making a positive therefrom by positioning a sensitive photographic layer in printing relation with the negative and illuminating the negative with light whose distribution over the negative is made up of predetermined relative amounts of a uniform portion and the portion corresponding to a color separation positive image of the original, the last mentioned color being a correcting color and different from that corresponding to the separation negative.

5. In a photo-mechanical process for the reproduction of a multi-colored original, the method of making a corrected color printer which comprises making a color separation negative, placing a sensitive photographic layer substantially in contact with said negative, and exposing the layer through the negative to a uniform beam of light and to a color separation positive image of the original, said last mentioned color being a correcting color and different from that corresponding to the negative.

6. In a photo-mechanical process for the reproduction of a multi-colored original, the method of making a corrected color printer which comprises making a color separation negative by exposing a sensitive photographic layer through its support, placing another sensitive photographic layer substantially in contact with said negative, and exposing the last-mentioned layer through the negative to a uniform beam of light and to a color separation positive image of the original, said last mentioned color being a correcting color and different from that corresponding to the negative.

ALEXANDER MURRAY.
